UNITED STATES PATENT OFFICE.

JOHN ERICSSON, OF NEW YORK, N. Y., ASSIGNOR OF ONE-HALF TO CORNELIUS H. DELAMATER AND GEORGE H. ROBINSON, BOTH OF SAME PLACE.

STEERING APPARATUS.

SPECIFICATION forming part of Letters Patent No. 245,469, dated August 9, 1881.

Application filed May 28, 1881. (No model.)

To all whom it may concern:

Be it known that I, JOHN ERICSSON, of the city, county, and State of New York, have invented certain new and useful Improvements in Steering Apparatus, of which the following is a specification.

My invention, which is especially adapted for torpedo-vessels and other vessels of war, consists in hanging the rudder of a vessel entirely below the water-line to a rudder-post which constitutes an upward prolongation of the keel, or which projects upward from a prolongation of the keel and does not project above the water-line, thus reducing the liability of the rudder being carried away by an enemy's shot.

The invention also consists in a novel arrangement of hydraulic cylinders, pistons, and connections for working the rudder, the cylinders being arranged on the exterior of the vessel below the water-line, upon each side of the keel, and the liquid for operating said pistons being conducted to said cylinders by pipes which extend to the interior of the vessel and are provided with suitable cocks or valves for regulating the flow of liquid through them.

In the accompanying drawings, Figure 1 represents a central longitudinal section of the after portion of a vessel, comprising a rudder and steering-gear embodying my invention; and Fig. 2 represents a plan view of a portion of the keel and the rudder, and a sectional view of the steering-cylinders and connections.

Similar letters of reference designate corresponding parts in both figures.

A designates the stern or after part of a vessel, which may be of any approved construction.

B designates the stern-post of the vessel, and C designates the propeller, and C' the stern-bearing for the propeller-shaft, all of which are of the usual or other suitable construction.

D designates the keel, and D' designates the rudder-post, which forms an upward prolongation of the keel in rear of the stern-post, and which, as here represented, is forged with the keel.

In lieu of being made in the same piece with the keel, the rudder-post might consist of a 50 separate piece erected upon a rearward prolongation of the keel.

Upon the rudder-post D' are two rearwardly-projecting lugs or arms, a; and E designates the rudder, which rests upon the lower lug or 55 arm, and has in it a slot or notch, b to receive the upper lug or arm. The rudder is secured in place by a pin, c, which may be inserted from above, and has bearings in the two lugs or arms, a, and which may be firmly fastened 60 within the rudder, and project sufficiently above the rudder to have an ordinary steering-gear applied, if desired.

It will be observed that the rudder and rudder-post are entirely below the water-line, and 65 this renders my invention particularly applicable not only to torpedo-vessels, but to all kinds of war-vessels, as the rudder is protected against shot and shell. As here represented, the rudder E extends forward of its 70 center of movement, and thus serves to partly balance it.

Referring, now, to the mechanism for controlling the rudder, F F designate two hydraulic cylinders arranged upon opposite sides 75 of the keel, upon the exterior of the vessel, and secured thereto by any suitable means. In each cylinder F is a piston, G, and the two pistons are connected by rods G' with arms E', projecting on opposite sides of the rudder E. 80 It will therefore be seen that by admitting liquid under pressure to one or the other of said cylinders F the rudder may be shifted as desired.

H H designate two pipes which extend forward from the cylinders F, one upon each side of the keel D, and which extend through the bottom of the vessel to a cock or valve, I, whereby the admission of liquid through either pipe to either cylinder and the exhaust of liquid from the other cylinder is controlled. 85

To the cock or valve I is secured a lever, d, to the opposite ends of which are connected cords, chains, or other flexible connections, e, which are passed over guide-pulleys f, and 90 thence to an ordinary steering-wheel located 95

within the vessel. This wheel only requires to make a sufficient portion of a revolution to work the valve-lever *d*.

The liquid for operating the steering-pistons 5 may be taken from a pump or any other source of pressure, and the cock or valve for controlling the admission of liquid to the steering-cylinders, and the means employed to operate said cock or valve, may be modified as circumstances 10 may require.

The arrangement of the steering-cylinders below the water-line, and in the position shown, upon each side of the keel, is very desirable, inasmuch as they are protected against injury 15 from shot, and their pistons are connected directly with the rudder without the necessity of passing any rods or moving connections through the sides of the vessel.

The vessel represented is constructed with 20 a double deck, or rather two decks, *J J'*, the space between which I propose generally to make about three feet high, and intend to fill with floats composed of or filled with cork, or floats consisting of bags of india-rubber or 25 other material inflated with air. The vessel is intended to be immersed to such depth that the under one, *J'*, of these decks will be below the water-line, and the portion of the vessel below it will be protected in a great degree 30 from enemy's shot by the surrounding water. In case of the upper deck, *J*, or any part of the vessel above the deck *J'*, being penetrated by a shot, such of the floats between the two decks as are not destroyed will continue to 35 give buoyancy to the vessel.

I also construct all across the vessel, above the decks and in front of the base of the smoke-stack, (the vessel being intended to be propelled by 40 steam-power,) a shield, *K*, composed of very heavy armor-plates, which are inclined up-

ward and backward in such manner as to deflect any shot or other projectiles that may strike it. This shield has a backing of solid timber, *L*, that would enable it to resist shot 45 which might strike it at, or nearly at, a right angle.

What I claim as my invention, and desire to secure by Letters Patent, is—

1. The combination, in a vessel, of a rudder-post which projects upward from a prolongation of the keel entirely below the water-line, and a rudder hinged thereto, and also entirely below the water-line, substantially as and for the purpose herein specified. 50

2. The combination, in a vessel, of a rudder having arms projecting from opposite sides, steering cylinders and pistons arranged upon the exterior of the vessel, one upon each side thereof, and connected with said rudder-arms, 60 pipes from said cylinders extending through the hull to the interior of the vessel, and a valve or valves for controlling the admission of liquid through said pipes to said cylinders, substantially as and for the purpose herein 65 specified.

3. The combination, in a vessel with the rudder-post projecting upward from a prolongation of the keel and the rudder hinged thereto, both being entirely below the water-line, of the 70 steering cylinders and pistons secured upon opposite sides of the keel and connected with the lower part of the rudder, pipes leading from said cylinders to the interior of the vessel, and a valve or valves for controlling the 75 admission of liquid through said pipes to said cylinders, substantially as and for the purpose herein specified.

J. ERICSSON.
